UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

SHEET-REGISTERING DEVICE.

Application filed October 6, 1921. Serial No. 505,731.

To all whom it may concern:

Be it known that I, HOWARD K. KING, a citizen of the United States, residing at Philadelphia, in the county of Philadelphia, 5 State of Pennsylvania, have invented a new and useful Improvement in Sheet Registering Devices, of which the following is a specification.

The invention relates to sheet registering 10 device for sheet feeding machines, and is particularly applicable to continuous press feeders. The object is to provide improved means for bringing the sheet to proper position or register before its delivery.

15 The invention comprises improved means for moving the sheet transversely its direction of delivery to or against a stop or gage adjustably positioned to limit its sidewise movement.

20 The invention comprises improved means for actuating the sheet either to the right or to the left as required, including a reversible actuating mechanism adapted to change the initial movement of the gripper supporting 25 means, for right or left hand guide as desired; means for adjusting the position of the actuating device, improved means for both preliminary and for final adjustment of the position of the stop or gage; means for 30 rendering inactive the side guide mechanism on one side of the machine, while rendering active the side guide mechanism on the other side, and vice versa; improved adjustable frictional means for maintaining the side 35 guide actuating mechanism in desired operative position, but adapted automatically to assume another position of adjustment when required by the position of the stop or gage, and means for arbitrarily changing the tension 40 of the frictional means either to render its normal operation effective, without preventing its automatic adjustment, or for rendering the actuating mechanism connected therewith ineffective, when it is desired to put said side-guide out of commission.

45 The invention also comprises means for producing a curve in the plane of the sheet on the line of its engagement with the stop or gage to render it more rigid and prevent it 50 from crumpling when pulled against the stop.

Referring to the drawings, which illustrate merely by way of example suitable means for the embodiment of my invention;

55 Fig. 1 is a side elevation of part of a sheet

feeding machine provided with my improvements.

Fig. 2 is a plan view showing my invention on a larger scale.

Fig. 3 is a section on line 3—3 of Fig. 2, 60 on a still larger scale.

Fig. 3^a is a fragmentary detail in part section.

Figure 4 is an elevation directed especially to the rack and pinion actuating 65 means.

Fig. 5 is a plan view of same.

Fig. 6 is a similar view showing the position of elements reversed.

Fig. 6^a is a fragmentary detail, in section. 70

Fig. 7 is a front elevation of the gripper and stop mechanism.

Fig. 8 is a side elevation of same, with parts broken away.

Fig. 9 is a plan view of same.

Fig. 10 is a section on line 10—10 of Fig. 9.

Fig. 11 is a side elevation of the channel and stop element.

Fig. 12 is a front elevation of the lower 80 jaw element and the supporting means, of the gripper.

Fig. 13 is an elevation of the upper jaw element of the gripper.

Fig. 14 is a plan view of same.

Fig. 15, Sheet 2, is a detail, in part section, 85 of the means for final adjustment of the stop element.

Fig. 16 is a sectional detail showing means for supporting the bar carrying the stop elements. 90

Fig. 17, Sheet 5, is a detail showing the spring clip for holding a gripper out of action.

Similar numerals refer to similar parts 95 throughout the several views.

By way of example I have shown my improved mechanism as applied to a sheet feeding machine for rotary printing presses; the frame 20 and table 21 supports the usual delivery apron 25, from which the sheets 100 are delivered to the press roller 22 of the printing press.

In order to secure the proper guiding of the sheets so that they will register, I have provided improved mechanism for the side guiding of the sheets in order to bring them into position for delivery to the press. This comprises broadly a suitable adjustable side stop or gage mechanism supported in the frame 23, and a suitably actuated gripper 110

mechanism for pulling the sheets sidewise against the gage. This gripper mechanism is supported by the frame 24, connected to the apron structure 25, pivoted as at 26, so that said frame 24 may be lifted with the apron away from the table 21 when desired. The vertical adjustment of frame 24 with respect to the table 21 is secured by the threaded bolt 27 resting upon the plate 28 on table 21.

The gage and gripper mechanisms are provided in duplicate, for registering the sheet either to the right or to the left, as the circumstances may require. A description therefore of one gage and gripper mechanism will suffice for both.

Gage mechanism.

The normally stationary gage mechanism comprises the body 29, adjustably secured upon the rod 30, which is supported in the frame 23. This body 29 is mounted on the bar 30, which is normally stationary, and has preliminary adjustment thereon by means of the following mechanism. The bar 30 is held in reasonably tight engagement with the frame 23 by means of the plate 31, engaging the flat surface 32 of said frame 23. The efficiency of engagement between plate and frame is maintained by the clamp screw 33, see Fig. 16. This also prevents the turning of the bar 30 in the frame 23. The body 29 is secured in position on the bar 30 by means of the set-screw 34. The graduations or marks 35 on bar 30, correspond to the sizes of the sheets to be operated upon, and serve to secure the proper position of initial or preliminary adjustment. Both ends of the bar are provided with these graduations. A further means for adjustment, in order to secure exact registration, consists in providing the adjusting screw 36, threaded into the end of bar 30, as shown in Fig. 15. This adjusting screw 36 has a swiveling engagement with the frame 23 and is operated manually by means of the knurled head 37.

The body or formation 29, as shown in Figs. 7 to 11, inclusive, comprises the arc-shaped or convex upper surface 38, having the channel 39 extending transversely the delivery movement of the sheet. Near the rear end of channel 39, and flanking the same, are the upwardly projecting stops or gages 40. Formation 29 is also provided with the upwardly extending arm 41 to the rear of the gages or stops 40.

Gripper mechanism.

In frame 24 is slidably secured the bar 42, as shown in Fig. 3. This bar 42 is clamped to the arm 43, which is slidably connected with the bar or shaft 42', see Fig. 3a. This serves to prevent the bar 42 from turning on its axis.

On bar 42 is adjustably mounted the body or formation 44. The position of adjustment is secured in the following way: Through the top of the body 44 are provided the holes 45 in which are seated the washers 46 of leather or other suitable similar material. These washers 46 are adapted to engage the bar 42, see especially Figs. 8 and 10. Above the washers 46 are provided metal washers or plates 47, recessed or cupped at the upper side to receive the ends of the set-screws 48. These two set-screws threaded in the resilient plate 49, and are held in position of adjustment by the lock nuts 50. Through the middle portion of plate 49 projects the tension screw 51, threaded into the body portion 44, having a flange for engaging the plate 49 and provided with the knurled head 52.

It will thus be seen that when the screws 48 are properly adjusted to exert pressure on bar 42 through the washers 46, this pressure becomes effective by screwing down the screw 51; and thus the body 44 is normally held in the desired position of adjustment on the bar 42.

It will be understood that when the screws 48 are properly adjusted, such adjustment becomes effective by tightening the clamp plate 49 by means of the screw 51, and thus the desired frictional engagement of member 46 on bar 42 is secured. By releasing the pressure of plate 49 by partially withdrawing clamp screw 51, this frictional engagement becomes ineffective.

The body or member 44 is provided with the downwardly extending arm 53, having at its lower end the horizontally extending gripper-jaw member 54. This jaw member 54 is slidably seated in the channel 39 of member 29. In the lower end of arm 53 is pivotally secured, as at 55, the plate 56. To this plate is secured the upper gripper jaw member 57, and also the two flanking fingers 58, see Fig. 14. A post 59 is also secured to the pivoted plate 56, and at the upper end of the plate 56 is secured the pivoted hook 60 for engaging the end of tension spring 61. The other end of spring 61 is secured to the bent-over end 62 of rod 63, slidably supported in the lug 64 of body or member 44. This rod 63 is held in position of adjustment by the knurled-headed nut 66, threaded on said rod 63, (see Figs. 2 and 7 to 10 inc.).

When it is desired to hold a gripper out of action, the tension on plate 49 is relieved and the upper end 67 of arm 41 of body or member 29, is brought over into engagement with lug 65 of body 44; these two elements 65 and 67 are then secured and held together by any suitable means, as for example, by the spring clip 68, see Figs. 2 and 17. At the same time, the engagement of post 59 with arm 41, serves, when the parts

are in this position, to hold the gripper jaw member 57 and the flanking fingers 58 in the open position, to permit the sheet to travel beneath them.

⁵ *Actuating mechanism for the gripper jaws.*

As above stated, the body portion 44, to which are secured the gripper jaws 54 and 57, is held in frictional engagement with bar 42, so that normally the body 44 will move with bar 42 in its reciprocating movements.

The reciprocating movement of the bar 42 is secured by the following mechanism.

¹⁵ Bar 42 is provided with the rack portion or serrations 69 adapted to cooperate with the pinion 70. Pinion 70 also cooperates with the rack bar 71 connected to the slide block 72, sliding on the plate or table 73. ²⁰ This rack bar 71 and slide block 72 are adjustably connected to the connecting rod 74 by means of the threaded end 75, threaded into link 76 pivotally connected to slide block 72 by the pivot bolt 77, which is also connected to the rack bar 71. The bar 71 and block 72 are held in slidable engagement with the table 73 by means of the clamp plate 78.

²⁵ The other end of connecting rod 74 is secured, through the rock lever 79 and link 80, to the lever 81, pivotally mounted at 82, and provided with the roller 83 adapted to engage the cam 84, having proper synchronous rotation with the other operations of the machine. The rotating of the cam 84 gives the required reciprocating movement of rod 74 and, consequently, of rack bar 71 and pinion 70, and consequently the proper or required reciprocating movement of bar 42 and the gripper mechanism carried thereon; the cam 84 being so formed as to secure the required reciprocating movements of the gripper mechanism. That is, to pull the sheet at a moderate speed, dwelling out until the sheet has passed out of the way, and then moving in quickly before the next sheet reaches the guide.

³⁰ It will be noted that as shown in Fig. 5, the rack bar 71 is on one side of pinion 70, while as shown in Fig. 6, the rack bar is in cooperation with the other side of the pinion.

³⁵ The means for making it possible to shift or carry the rack bar from one side of the pinion to the other, comprise the threaded connection at 75, and the block 78 provided with the flange 85 removably secured to either post 86 or 87 by the cotter 88. That is to say, starting with the parts as shown in Fig. 5, in order to change the position shown in Fig. 6, it is only necessary to withdraw the cotter 88 from post 86, then remove the block 78 from post 86, lift the slide block 72 from table 73, and turn it over, so as to bring the rack bar 71 from

position shown in Fig. 5, to position shown in Fig. 6. The rack bar is then secured in its new position by placing the block 78 on post 87 and inserting the cotter 88 in place as shown, see Figs. 6 and 6^a. The ⁷⁰ thread on connecting rod 74, as at 75, is so fine that a half turn of link 76 with block 72, which is all that is required, does not substantially affect the required effective length of rod 74. ⁷⁵

The object of transferring the rack bar 71 from one side of the pinion 70 to the other, and vice versa, is to secure the proper initial actuation of the gripper element, relatively to the cycle of operation of the machine, depending upon whether the right hand gripper or the left hand gripper is to be used. In other words, the forward movement for one gripper would be, in direction, the reverse of the forward movement of the other gripper; obviously therefore, the direction of initial movement of bar 42, will depend upon which side of pinion 70 the rack bar is in cooperation during its initial movement. When it is desired to bring one gripper into operation and put the other out of commission, it is only necessary to effect the frictional cooperation of the gripper bodies on bar 42 as above described, and then turn the rack bar 71 over from one side of the pinion 70 to the other, as described, without disturbing any other parts of the machine. ⁹⁰

⁹⁵ The rack bar 71 is placed on the right side of the pinion 70 when working the right hand gripper and on the left side of the pinion when working the left hand gripper. ¹⁰⁰

The operation.

The sheet is brought to the forward part ¹⁰⁵ of the delivery apron and, just before delivering to the press, it is moved either to the right or to the left against the stop, or gage, in order to secure its proper register. Depending upon whether it is to be pulled to the right or to the left, one of the grippers and its cooperating stop or gage device are moved out of the way or path of travel of the sheet, and the gripper mechanism is released from its frictional cooperation with the bar 42 as already described. The other gage device is secured to the bar 30 in approximately proper position with regard to the size of the sheet to be operated upon. The graduations 35 on said bar are utilized in this connection. An additional and final adjustment of the stop member 29 is secured by the adjusting screw 36, so that, by a few tests, the exact register of the delivered sheet is secured. A further graduation is preferably provided on the face of a part of frame 23 surrounding screw 36 and adjacent knurled-head 37, as shown in Fig. 4. ¹¹⁰

¹¹⁵ The gripper member 44 is then adjusted approximately, by means of the frictional ¹²⁰

engagement above described, to the bar 42. The actuation of bar 42, in the manner above described, causes the required reciprocating movement of the gripper jaws.

5 Taking for example the arrangement shown in Figs. 2, 7 and 10, with the gripper and stop or gage mechanisms, on the right being used, it will be noted that the body 44 is provided with the two downwardly 10 projecting lugs 64 and 65, and that the member 29 has the upwardly projecting lug 67 which projects between lugs 64 and 65 and in their line of travel. It follows that if, during the reciprocation of bar 42, there 15 should be a tendency of body 44 to travel in either direction beyond a required distance relatively to member 29, the projection 67 will engage either abutment 64 or 65 and stop the further movement of 44; that is, 20 the frictional engagement between 44 and bar 42 is such that the member 44 will normally travel the full stroke of the bar, in either direction, when unobstructed, but will permit the travel of the bar 42 beyond 25 its movement in case either or both lugs engage with the stop 67.

It will also be noted that when the body 44 is in the position shown in Fig. 7, the jaw 57 is in the closed position cooperating with the jaw member 54. When however the body 44 moves to the forward position that is to the left, as shown in Fig. 10, the post 59 on plate 56 engages the arm or projection 41 of body 29 and causes the actuation of 30 plate 56 and the corresponding actuation and lifting of jaw member 57 and the flanking fingers 58 into the open position, as shown in said Fig. 10. Immediately however upon movement of body 44 to the right, the jaw member 57, in response to the tension of spring 61, moves toward the closed position, and finally, into the closed position as soon as post 59 leaves the abutment 40 on arm 41; so that, in the movement of the gripper jaws toward the left into the path of travel of the sheet, the jaws are forced 45 open by the engagement of post 59 with abutment on 41, and in the movement to the right of member 29, the jaw members immediately begin to close and finally do close 50 in time to grasp the sheet and pull it over to the stops or gages 40, before the end of said movement to the right. After the sheet 55 is brought into engagement with the stops 40, the further movement of the jaws results in a slipping of the jaws from the sheet until they finally pass beyond the margin thereof. The proper frictional engagement 60 of the jaws, sufficient to move the sheet to the stops, and yet permitting the release of the sheet after it reaches the stops, is secured by the adjustment of the tension of the spring 61 by operation of the knurled-headed nut 66.

65 In order to prevent a crumpling or buck-

ling of the sheet after it has engaged the stops or gages 40, due to the pull of the gripper jaws, I have found that the most effective way is to form the portions of the edges of the sheet, which engage the stop members 40, into curved lines and the parts adjacent thereto into correspondingly curved planes. This is accomplished by providing the upper surface, as at 38, of the member 29 in a curved or convex formation 70 and then pressing the sheet down on both sides of the jaws by means of the fingers 58, which close upon the sheet simultaneously with the closing of the jaws. It makes practically no difference what the formation of 75 the sheet edge is between the jaws, but the important thing is that the edges which engage the faces of the stops or gages 40 should have a curved extension so as to stiffen that part of the sheet in the lines of 80 said engagement, on both sides of the jaws, as the jaws are being slipped therefrom.

It will also be noted that the channel 39, in which the lower jaw is adapted to reciprocate, is of greater depth than the cross-sectional dimension of the lower jaw, so as to permit a certain amount of adjustment therein. This adjustment of the lower gripper jaw, and consequently the position of the upper face of said jaw, with respect 95 to the flanking surfaces 38, is secured by means of the adjusting screw 27, the head of which rests upon the plate 28 secured to the table 21, as shown in Figs. 3 and 4.

What I claim is:—

1. In a sheet registering device, the combination of a supporting frame, a bar adjustably supported therein, a side stop adjustably secured thereto, means for securing a preliminary adjustment of the side stop 100 on the bar and means for securing final exact adjustment of the bar in the frame.

2. In a sheet registering device, the combination of an adjustably supported side stop, adjustably supported gripper mechanism, means for causing reciprocation of same, and means for securing, in said reciprocating movement during required periods, a moderate speed for pulling over the sheet, a dwell for permitting the sheet to pass from 110 the influence of the grippers, and a quick return movement into position for operating upon the succeeding sheet.

3. In a sheet registering device, the combination of an adjustably supported side stop, adjustably supported gripper elements, means for reciprocating the gripper elements, means for causing frictional cooperation between the gripper elements and the reciprocating means, adapted to permit movement of the reciprocating means beyond the required movement of the gripper elements, and means to secure automatic adjustment of the gripper elements with respect to the side stop.

4. In a sheet registering device, the combination of an adjustably supported side stop, adjustably supported gripper elements, means for reciprocating the gripper elements, adjustable means for causing frictional cooperation between the gripper elements and the reciprocating means, adapted to permit movement of the reciprocating means beyond the required movement of the gripper elements, and means to secure automatic adjustment of the gripper elements with respect to the side stop.

5. In a sheet registering device, the combination of an adjustably supported side stop, adjustably supported gripper elements, means for reciprocating the gripper elements, means for causing frictional cooperation between the gripper elements and the reciprocating means, adapted to permit movement of the reciprocating means beyond the required movement of the gripper elements, and means for releasing said frictional cooperation.

6. In a sheet registering device, the combination of an adjustably supported side stop, gripper elements for pulling the sheet against the stop and means forming the sheet, at its line of engagement with the stop, in the arc of a circle throughout the extension of the stop.

7. In a sheet registering device, the combination of an adjustably supported side stop, gripper elements for pulling the sheet against the stop and means, operating in unison with the closing movement of the gripper elements, for forming the sheet, throughout its line of engagement with the stop, in the arc of a circle.

8. In a sheet registering device, the combination of an adjustably supported side stop, cooperating gripper jaws, and means for reciprocating the same, and means, including an arm extending substantially at right angles with the extension of a gripper jaw, and an engaging formation connected with the stop, for causing the automatic opening and closing of the gripper jaws synchronously with their reciprocating movement.

9. In a sheet registering device, the combination of an adjustably supported side stop, cooperating gripper jaws and means for reciprocating the same, means, including a spring controlled arm extending substantially at right angles with the extension of a gripper jaw and an engaging formation connected with the stop for causing the automatic opening and closing of the gripper jaws synchronously with their reciprocating movement, and a hand operated threaded formation for varying the tension of the spring.

10. In a sheet registering device, the combination of an adjustably supported side stop, cooperating gripper jaws, means for

reciprocating the same, spring means for securing frictional cooperation between the gripper jaws and the sheet, and a hand operated threaded formation as the sole means for varying the tension of the spring. 70

11. In a sheet registering device, the combination of means forming an adjustable side stop, having a channel and channel flanking convex sheet engaging surfaces, cooperating gripper jaws, one extending in said channel, and means for adjusting the jaw in said channel in order to secure the desired relation between the upper surface of the jaw and said flanking convex surfaces. 75

12. In a sheet registering device, the combination of an adjustably supported side stop, cooperating gripper device, a reciprocating supporting bar therefor, means for causing frictional cooperation between the gripper device and the supporting bar, means for adjusting the efficiency of said friction and means for releasing said frictional cooperation without affecting said adjustment. 80

13. In a sheet registering device, the combination of an adjustably supported side stop, cooperating gripper device, a reciprocating supporting bar therefor, means for causing frictional cooperation between the gripper device and the supporting bar, means for adjusting the efficiency of said friction, means for releasing said frictional cooperation without affecting said adjustment, and means for securing the gripper device in inactive position after such release. 95

14. In a sheet registering device, the combination of an adjustably supported side stop, cooperating gripper device, a reciprocating supporting bar therefor, means for causing frictional cooperation between the gripper device and the supporting bar, means for adjusting the efficiency of said friction, means for releasing said frictional cooperation without affecting said adjustment, and means for reciprocating the bar, including a cam adapted to cause a gradual movement during part of said reciprocation, a dwell, and then an accelerated movement. 105

15. In a sheet registering device, the combination of an adjustably supported side stop, cooperating gripper device, a reciprocating supporting bar therefor, means for causing frictional cooperation between the gripper device and the supporting bar, means for adjusting the efficiency of said friction, means for releasing said frictional cooperation without affecting said adjustment, and means for reciprocating the bar, including a pinion, a cooperating rack bar, and means whereby the rack bar may be translated from one side of the pinion to the other in order to reverse the direction of initial actuation. 120

16. In a sheet registering device, the combination of an adjustably supported side stop, cooperating gripper device, a reciprocating supporting bar therefor, means for causing frictional cooperation between the gripper device and the supporting bar, means for adjusting the efficiency of said friction, means for releasing said frictional cooperation without affecting said adjustment, means for reciprocating the bar, including a rack formation on the bar, a cooperating pinion, a reciprocating rack-bar also cooperating with the pinion, a slide block connected with the rack bar, a slide table for said block and disengageable means for securing movable cooperation between slide block and table, adapted to permit turning the block over in order to disengage the rack-bar from one side of the pinion and to bring it into operative relationship with the other side of the pinion.
17. In a sheet registering device, the combination of an adjustably supported side stop, cooperating gripper device, a reciprocating supporting bar therefor, means for causing frictional cooperation between the gripper device and the supporting bar, means for adjusting the efficiency of said friction, means for releasing said frictional cooperation without affecting said adjustment, means for reciprocating the bar, including a pinion, a cooperating rack bar, a cam for actuating the rack bar, means for establishing operative relationship between

the cam and rack bar, including a connecting rod having threaded adjustable connection with the rack bar and means, including said threaded connection, whereby said rack bar may be translated from one side of the pinion to the other in order to reverse the direction of initial actuation.

18. In a sheet registering device, the combination of a table, a frame secured thereto, a bar adjustably secured in said frame, and spaced above the table and extending transversely from one side to the other thereof, a side stop adjustably mounted on the bar, means for securing the stop to the bar in position of preliminary adjustment, and means for moving the bar in the frame for final adjustment.

19. In a sheet registering device, the combination of a table, a frame secured thereto, a bar adjustably secured in said frame and spaced above the table, a side stop adjustably mounted on the bar, means for securing the stop to the bar in position of preliminary adjustment, and means for moving the bar in the frame for final adjustment, the bar provided with graduations corresponding to different sized sheets, and the bar-moving means and the adjacent part of the frame provided with graduations and a cooperating mark for indicating the final and accurate position to which the edge of the sheet is to be brought in its side registering movement.

HOWARD K. KING.
